US0D1103774S

(12) **United States Design Patent** (10) Patent No.: **US D1,103,774 S**
(45) Date of Patent: ** Dec. 2, 2025

(54) **CONTAINER**

- (71) Applicant: **NICOVENTURES TRADING LIMITED**, London (GB)
- (72) Inventors: **Wesley Steven Jones**, Lexington, NC (US); **Nicholas H. Watson**, Westfield, NC (US); **Pankaj C. Patel**, Clemmons, NC (US); **Laya Katina Palmer Horton**, Winston-Salem, NC (US); **Ryan A. Bailey**, Raleigh, NC (US); **Michael E. Laut**, Raleigh, NC (US); **Prasad Joshi**, Raleigh, NC (US)
- (73) Assignee: **Nicoventures Trading Limited**, London (GB)
- (**) Term: **15 Years**
- (21) Appl. No.: **29/850,292**
- (22) Filed: **Aug. 18, 2022**

CLAIM

The ornamental design for a container as shown and described.

DESCRIPTION

FIG. 1 is a top perspective view of a container of the present invention showing our new design;

FIG. 2 is a bottom perspective view thereof;

FIG. 3 is a left elevation view thereof

FIG. 4 is a right elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings depict portions of the container that form no part of the claimed design.

1 Claim, 6 Drawing Sheets
